Arthur G. Fraser & Co.

UNITED STATES PATENT OFFICE.

PAUL MAUSER, OF OBERNDORF, WÜRTEMBERG, GERMANY, ASSIGNOR TO
THE WAFFENFABRIK MAUSER, OF SAME PLACE.

SHELL-EXTRACTOR FOR BOLT-GUNS.

SPECIFICATION forming part of Letters Patent No. 431,669, dated July 8, 1890.

Application filed December 2, 1889. Serial No. 332,197. (No model.) Patented in Belgium May 25, 1889, No. 86,375; in Germany July 3, 1889, No. 49,877; in England November 12, 1889, No. 18,014; in Italy December 31, 1889, No. 26,450/137, and in Spain February 1, 1890, No. 10,226.

To all whom it may concern:

Be it known that I, PAUL MAUSER, a subject of the King of Würtemberg, Empire of Germany, and a resident of Oberndorf-on-the-Neckar, in the Kingdom of Würtemberg, German Empire, have invented a certain new and useful Cartridge-Shell Extractor with Radial Guides for Breech-Loading Bolt-Guns, of which the following is a specification.

10 This invention is the subject-matter of Letters Patent in Germany, No. 49,877, dated July 3, 1889; in Belgium, No. 86,375, dated May 25, 1889; in England, No. 18,014, dated November 12, 1889; in Italy, No. 26,450/137, dated December 31, 1889, and in Spain, No. 15 10,226, dated February 1, 1890.

This invention relates to that part of a bolt-gun which is designed for drawing the shells of the exploded cartridges out of the gun-barrel, and which is usually termed an "extractor;" and the invention comprises more particularly certain improvements in such extractors whereby the latter are rendered reliable in action and strong and simple in construction.

25 The invention is intended primarily for bolt-guns the bolts of which are provided with recoil or locking projections on their front ends, and which do not have separate bolt-heads. It may, however, be applied to bolt-guns the bolts of which have a separate head, if desired.

In the accompanying drawings, Figure 1 is a side view of the front end of a bolt. Fig. 35 2 is a front view thereof. Fig. 3 is a horizontal axial section of Fig. 1, a cartridge being shown in dotted outline. Figs. 4, 5, and 6 are views corresponding to Figs. 1, 2, and 3, showing a modified method of applying my invention to that class of bolts having separate bolt-heads.

In the drawings, the bolt *a* is shown with recoil projections *a*⁵ *a*⁵ on the opposite sides of its front end. One of these projections is 45 deeply grooved or slotted for the admission of the ejector for throwing out the cartridge-shells. The other projection is formed with a radial recess *a'*. The extractor is made in the form of a block *f*, which plays in this re-

cess, and is provided with the usual claw *f'*, 50 designed to engage the rim at the base of the cartridge-shell for the purpose of withdrawing the latter after firing. The block *f* is provided with lateral guide-ribs, which play in slideways or grooves *b b*, formed in the sides 55 of the radial recess *a'*.

Referring to the construction shown in Figs. 1, 2, and 3, on the back of the block *f*, opposite the claw *f'*, is provided a lug *f*², which plays in a radial bore in the projection *a*⁵, communicating with the radial recess, in which the extractor-body *f* slides. A screw *f*³, the flat head of which fits into this bore, passes through a hole in the lug *f*², and is screwed into the material of the bolt *a*. Between the 65 head of the screw *f*³ and the lug *f*² is placed a coiled spring. By this construction the extractor *f* will yield outwardly if the claw *f'*, with its oblique face, is pressed against the edge of the cartridge-base, as is done in pushing the cartridge home into the barrel by the bolt *a*, and after having passed this edge the extractor *f* will snap back with the said claw *f'* in front of the rim of the cartridge. The 70 straight guides or slideways *b b* and the radial position of the extractor *f* give to it great stability and strength. In case the bolt *a* possesses a separate head coupled with it in any suitable way the extractor just described can be used, or, if preferred, it may be slightly 75 altered with reference to the means for imparting elasticity to it. Such a construction is represented in Figs. 4, 5, and 6. The bolt-head *a*⁶ has wings corresponding to the recoil-projections *a*⁵ of the bolt *a*. The body *f* of the 80 extractor is placed in a recess formed in that wing which is not slotted for the shell-ejector. It is guided in the radial grooves or slideways *b b* in the recess by ribs exactly as hereinbefore described; but instead of being actuated by 85 a coiled spring the lug *f*² on the back of the body *f* is made a flat spring, being elongated to a long tail *f*², which is placed in a longitudinal groove formed in the neck of the head, which neck fits snugly into the bolt *a*, 90 and by which the head *a*⁶ is coupled with the bolt. The back portion of the tail *f*² fills up the groove in the neck, but the fore part is 95

made thinner and elastic. The effect is the same as that of the extractor shown in Figs. 1 to 3 and described above.

I claim as my invention the following-defined novel features and combinations, substantially as hereinbefore specified, namely:

1. The combination, with a bolt having a recoil projection at its front end and formed with a radial recess in said projection, of a shell-extractor consisting of a block mounted in said recess and movable radially therein, provided with a claw on its front side and a spring for pressing it inwardly.

2. The combination, with the bolt having a radial recess in its front end or head and radial slideways at the sides of said recess, of a shell-extractor consisting of a block mounted in said recess, formed on its opposite sides to gage said slideways, and provided with a

claw at its front and a spring for pressing it inwardly.

3. The combination, with the bolt having a radial recess in its front end or head, of a shell-extractor consisting of a block mounted in said recess and movable radially therein, provided with a claw on its front side and formed with a lug on its rear side, a coiled spring in said recess behind the block, pressing inwardly against said lug, and a screw passing through the spring, screwed into the bolt, with its head arranged to close the recess and receiving the reaction of the spring.

This specification signed by me this 2d day of September, 1889.

PAUL MAUSER.
